UNITED STATES PATENT OFFICE.

FRANK H. WALKER, OF ATWOOD, KANSAS.

STARTING DEVICE FOR INTERNAL-COMBUSTION ENGINES.

No. 882,597.

Specification of Letters Patent. Patented March 24, 1908.

Application filed July 20, 1907. Serial No. 384,786.

To all whom it may concern:

Be it known that I, FRANK H. WALKER, a citizen of the United States, residing at Atwood, in the county of Rawlins and State of Kansas, have invented certain new and useful Improvements in Starting Devices for Internal-Combustion Engines, of which the following is a specification.

This invention is a starting device for internal-combustion engines, but more particularly that kind in which a combustible mixture of air and hydrocarbon under pressure is supplied to the working cylinder of the engine and is ignited therein to act directly on the piston.

The invention comprises an air-pump the cylinder of which is in communication with the explosion-chamber of the engine, and contains a plunger which is driven by the pressure from the explosion in said chamber. The compressed air is stored in a tank which is in communication with the explosion-chamber of the engine, and between the tank and said chamber is a device for charging the air with hydrocarbon. A suitable arrangement of valves controls the admission of the compressed combustible mixture to the engine.

In the accompanying drawing is shown an elevation of the starting-device, partly in section, only so much of the engine being shown as will suffice to show the connection of the invention therewith.

In the drawing 5 denotes the cylinder of an internal-combustion engine of ordinary construction; and 6 is the explosion-chamber thereof. On top of the cylinder is mounted, in any suitable manner, the cylinder 7 of an air-pump which contains a piston 8 connected by a rod 9 to a plunger 10. Around the rod is coiled a spring 11 which is confined between the top of the piston and a shoulder 12 formed on the inner wall of the pump-cylinder. Above the plunger 10, the pump-cylinder has an inlet-valve 13, and an outlet which is a pipe 14 leading to a tank 15 in which the compressed air is stored. The pipe 14 has a check-valve 16 to prevent return of the air to the pump-cylinder.

In the pump-cylinder, above the shoulder 12, is a partition 17, and around the rod 9 between this partition and the bottom of the plunger 10, is coiled a spring 18 to cushion the return movement of the piston and plunger. The outward movement of the piston is cushioned by means of a stud 19 lo-

cated on top of the plunger 10 so as to enter the outlet-pipe 14 at the extremity of the outward stroke of the plunger. The stud 19 has a small passage extending from the top 60 to the side thereof for the purpose of preventing the formation of a vacuum when the plunger descends. The pump-cylinder communicates with the explosion-chamber 6 of the engine by a pipe 20 containing a valve 65 20^a by means of which communication between said cylinder and chamber is established or cut off.

The pipe 14 has a branch 21 leading to the explosion-chamber 6 of the engine, and said 70 branch-pipe has a by-pass in which is located a carbureter. The carbureter comprises a tank 22 containing a supply of liquid hydrocarbon indicated at 23, above the level of which is arranged a strainer 24 composed of 75 two layers of canvas with a packing of absorbent material therebetween. The by-pass heretofore referred to comprises a pipe 25 extending from the pipe 21 into the tank 22, the mouth of the pipe 25 being located 80 below the level of the liquid 23 in the tank. The outlet from the tank is by a pipe 26 which enters the bottom thereof and extends through the liquid 23 and the strainer 24, the mouth of said pipe being located above 85 the strainer and the liquid. The pipe 26 communicates with the pipe 21.

The passage of air through the by-pass and into the engine is controlled by valves 27 and 28, respectively, the former being located in 90 the pipe 21 in advance of the junction of the pipe 25 herewith. The valve 28 is located in the pipe 21 between the junction of the pipes 25 and 26 herewith. When the valve 27 is open and the valve 28 is closed, the entire supply of air passes through the carbureter, and when the valve 28 is partly open only a portion of the air flows through the carbureter so that by operating said valve 95 the richness of the combustible mixture is 100 readily regulated.

The operation of the device is as follows: After the engine has been started a portion of the pressure from each explosion in its cylinder is directed against the piston 8, 105 whereby it is driven outwardly. As the pump-piston is connected with the plunger 10 the latter moves outwardly with the former and forces the air into the tank 15. The outward movement of the pump-piston 110 compresses the spring 11, and when the engine exhausts the spring expands and re-

turns the piston and plunger whereupon air is admitted to the pump-cylinder through the valve 13. At the next impulse of the engine more air is pumped into the tank and this is continued until the pressure therein minus the tension of the spring 11 equals the explosion pressure of the engine, whereupon the pump-piston will remain stationary. The pump can also be stopped by shutting 10 the valve 20^a.

Before the starting-device is charged as herein stated, the engine will have to be started manually but after this the engine can be started by simply turning on air from 15 the tank 15 which is done as follows: The valve 27 is opened and the valve 28 is partly closed, whereby the air from the tank passes through the pipe 21, into the pipe 25, and through the liquid hydrocarbon in the tank 20 22. The charge of vaporized hydrocarbon is then taken up by the pipe 26 and joins with the fresh air in the pipe 21 and is delivered by the latter pipe under pressure to the explosion-chamber of the engine and there- 25 in ignited in the ordinary manner. If after the first charge the engine fails to take its own mixture, another charge can be given it. In practice, only a small portion of the stored air is necessary to start the engine and 30 for this reason a large storage of air is not necessary. If desired, the valve 28 can be entirely closed so that all of the air will flow through the carbureter. After the engine

has worked up its own feed the starting-device will be cut out by shutting the valve 27. 35 Before stopping the engine, the air-pump will be cut in to recharge the tank 15 for the next run.

The device herein described can be readily fitted to any ordinary internal-combustion 40 engine without altering the construction thereof, and it is simple in construction, economical and reliable in operation.

I claim:

1. The combination with an internal-com- 45 bustion engine, of a carbureter, a source of compressed air, a pipe connecting said source with the explosion chamber of the engine and having a branch leading to the carbureter, and an outlet from the carbureter 50 connecting with the first mentioned pipe.

2. The combination with an internal-com- 55 bustion engine, of a carbureter, a source of compressed air, a pipe connecting said source with the explosion chamber of the engine and having a branch leading to the carbureter, an outlet from the carbureter 60 connecting with the first mentioned pipe, and valves in said pipe on opposite sides of the junction of the branch pipe therewith.

In testimony whereof I affix my signature, in presence of two witnesses.

FRANK H. WALKER.
